United States Patent Office

Des. 175,597
Patented Sept. 20, 1955

175,597

TRELLIS

Alfred K. Hauser, Chicago, Ill.

Application September 17, 1953, Serial No. 26,854

Term of patent 14 years

(Cl. D35—3)

Fig. 1 is a front elevational view of a trellis showing my new design;

Fig. 2 is a side elevational view; and

Fig. 3 is a bottom plan view thereof.

I claim:

The ornamental design for a trellis, as shown.
